MECHANICAL REFRIGERATOR CABINET

Filed March 7, 1927

Fig. 1

UNITED STATES PATENT OFFICE

RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY

MECHANICAL REFRIGERATOR CABINET

Application filed March 7, 1927. Serial No. 173,234.

This invention relates to mechanical refrigeration and more particularly to refrigerator cabinets adapted to house the refrigeration apparatus as well as to provide the refrigerating chamber or chambers. Such cabinets ordinarily provide a compartment, usually beneath the refrigerating chamber, in which the machine parts of the apparatus, such as pump and motor, are placed.

Where mechanical means are provided for moving air through the machine compartment any ordinary mass insulation, such as a conventional cork board, interposed between the compartment and the refrigerating chamber is adequate to protect the latter against heat generated in the compartment. Such constructions are well known and commonly used. Where, however, no mechanical air moving means are provided, it has hitherto been thought necessary to place the machine elements above the refrigerating chamber.

One object of the invention is to provide an improved form of cabinet permitting apparatus units which have no machine driven cooling means to be placed below the refrigerating chamber. Another object is to provide improved means for diverting heat from the refrigerating apparatus away from the low temperature chamber disposed above it. Other objects will be apparent from the detailed description which follows:

The invention provides means for taking care of convected heat by deflecting air currents ascending from the machine or apparatus units away from the bottom of the refrigerating chamber and for directing the same into the space about the cabinet with some velocity, so that cool air may constantly move into the machine compartment to replace the heated air. In order that the heated air may not lie dead in contact with the "ceiling" of the machine compartment, a ceiling member in the form of a deflector is arranged to slope outwardly. The slope of the deflector may be double so that the latter is V shape in end elevation and in addition may be inclined so that all air which contacts with the deflector must move outwardly and upwardly. With such an arrangement the air

leaves the compartment on at least two sides thus insuring ventilation of the compartment in case the cabinet is set close to a wall on one side. Since contact of the heated air with the deflector heats the latter, the invention further contemplates the use of one or more additional deflectors spaced above the first and conforming generally to the shape of the first. The cabinet provides inlet openings at the bottom of the compartment and outlet openings adjacent to the top toward which the deflectors direct all heated air as it rises. The arrangement is preferably such that movement of air is provided for on both sides of all the deflectors. The invention further prevents radiated heat from reaching the bottom of the refrigerating chamber by providing at least the lower of the deflecting members and preferably all of them, with bright reflecting surfaces on the lower side.

In order to illustrate the invention, one concrete embodiment thereof is shown in the accompanying drawings in which:

Fig. 1 is a front elevational view of a self-contained refrigerating cabinet intended for household use the lower part of the cabinet being shown in section; and

Fig. 2 is an end elevational view of the cabinet shown in Fig. 1 with the lower portion of the machine compartment in section.

In the embodiment of the invention chosen for the purpose of illustration, the cabinet A provides a refrigerating chamber B formed with walls of heat insulating material such as cork and beneath said chamber a compartment C containing at least a part of the refrigerating apparatus for extracting heat from chamber B. Upon a bridge piece 3 in compartment C is supported a prime mover, such as an electric motor 4, arranged to drive a pump or compressor 5, the two machines being coupled together to form a sealed motor-pump unit 4, 5. Pump 5 withdraws vaporized refrigerant from an evaporator element 6 in chamber B through a pipe 7 and discharges the same at higher temperature and pressure through a pipe 8 into the top of a natural draft condenser 9 which may be secured to the back of cabinet A as shown

and which returns the working substance to the evaporator through the feeding device or so-called expansion valve 10.

In order to dissipate the heat generated in the machine compartment C the entire lower portion of the compartment is open, save for bridge piece 3, to provide an inlet for air and adjacent the top of the compartment are provided a plurality of air outlets 11. The rising currents of heated air are arranged to be deflected to outlets 11 and kept away from the bottom of refrigerating chamber B. To this end a deflector 12 is arranged to form a false top or ceiling for the machine compartment in spaced relation to the bottom of chamber B. Deflector 12 separates or diverts the rising currents from points substantially centrally of compartment C towards outlets 11 and for this purpose is preferably generally V shaped as shown in side elevation in Fig. 1. Moreover, deflector 12 is arranged to have a generally upward inclination from the back to the front of compartment C as indicated in Fig. 2.

As a still further protection to chamber B at least one more deflector member is provided between deflector 12 and chamber B and in spaced relation to both. This second deflector 13 is generally similar in shape and arrangement to deflector 12 and cooperates with auxiliary outlet openings 14 and 15 at the ends of the cabinet and directly about the outlets 11. Outlets 11, 14 and 15 at each end of the cabinet may be provided by a single elongate generally rectangular opening 16 in the wall of the cabinet (Fig. 2). A series of inlet openings 17 which may be graduated in size as shown, are provided in the back wall of compartment C approximately on the contact line of deflector 13 so as to admit air to the space above and below deflector 13 with the result that provision is made for moving currents of air both above and below both deflectors to carry away the convected heat. To protect the bottom of chamber B against radiated heat the deflector members have bright reflecting under surfaces directed toward the motor-pump unit 4, 5. By preference deflectors 12 and 13 are formed of a bright metal such as tin.

With the arrangement above disclosed the air space above the uppermost deflector may be kept very close to the temperature of the room in which cabinet A is placed without recourse to fans or other moving parts, and thus leakage of heat through the mass insulation at the bottom of the refrigerator chamber B is not greater than through the other sides. By making the deflector of such shape as to direct rising currents of heated air to a plurality of sides of the box, it is evident that the protecting of the refrigerating chamber from the heat generated in the machine compartment is not seriously interfered with even when one end or side of the cabinet is

placed close against a wall. If desired, additional ventilation of compartment C may be effected by providing the sides or ends of the compartment, or both, with louvres as indicated at 18 in Fig. 1.

While a preferred form of the invention has been herein shown and described, it is to be understood that the invention is not limited to the specific details thereof, but covers all changes, modifications, and adaptations within the scope of the appended claims.

I claim as my invention:

1. In a refrigerator cabinet the combination with a chamber to be cooled and a compartment beneath said chamber for containing mechanical refrigerating apparatus, said compartment having an inlet for air currents and an outlet for the same adjacent the top of the compartment, of a deflector disposed above said apparatus for directing said air currents toward said outlet and away from the bottom of said chamber.

2. In a refrigerator cabinet the combination with a chamber to be cooled and a compartment beneath said chamber for containing mechanical refrigerating apparatus, said compartment having an inlet for air currents and an outlet for the same adjacent the top of the compartment, of a deflector presenting a bright reflecting surface toward said apparatus for directing said air currents toward said outlet and away from the bottom of said chamber.

3. In a refrigerator cabinet the combination with a chamber to be cooled and a compartment beneath said chamber for containing mechanical refrigerating apparatus, said compartment having an inlet for air currents and an outlet for the same adjacent the top of the compartment, of means for directing said air currents toward said outlet and away from the bottom of said chamber, and means providing for movement of air above said first-named means.

4. In a refrigerator cabinet the combination with a chamber to be cooled and a compartment beneath said chamber for containing mechanical refrigerating apparatus, said compartment having an inlet for air currents and an outlet for the same adjacent the top of the compartment, of a deflector disposed above said apparatus for directing said air currents toward said outlet and away from the bottom of said chamber, said cabinet having auxiliary air inlets and outlets between said deflector and the bottom of said chamber.

5. In a refrigerator cabinet the combination with a chamber to be cooled and a compartment beneath said chamber for containing mechanical refrigerating apparatus, said compartment having an inlet for air currents and outlets at the sides adjacent the top of said compartment, of a deflector within said compartment above said apparatus having a substantially centrally depressed portion ar-

ranged to direct said air currents away from the center of said compartment to the outlets in the sides of the same.

6. In a refrigerator cabinet the combination with a chamber to be cooled and a compartment beneath said chamber for containing mechanical refrigerating apparatus, said compartment having an inlet for air currents and outlets for the same adjacent the top of said compartment, of a deflector generally V shaped in end elevation within said compartment for directing said air streams to said outlets.

7. In a refrigerator cabinet the combination with a chamber to be cooled and a compartment beneath said chamber for containing mechanical refrigerating apparatus, said compartment having an inlet for air currents and outlets at the sides and adjacent the top of said compartment, of a deflector generally V shaped in end elevation within said compartment and inclined upwardly from one side of the compartment to the other for directing said air streams to said outlets.

8. In a refrigerator cabinet the combination with a chamber to be cooled and a compartment beneath said chamber for containing mechanical refrigerating apparatus, said compartment having an inlet for air currents and outlets at the sides and adjacent the top of said compartment, of means in said compartment for directing said air currents upwardly and outwardly to said outlets and away from the bottom of said chamber, and means providing for movement of air between said first named means and said chamber.

9. In a refrigerator cabinet the combination with a chamber to be cooled and a compartment beneath said chamber for containing mechanical refrigerating apparatus, said compartment having an inlet for air currents and an outlet for the same adjacent the top of the compartment, of a deflector disposed above said apparatus for directing said air currents toward said outlet and away from the bottom of said chamber, and a second deflector above and in spaced relation to said first deflector.

10. In a refrigerator cabinet the combination with a chamber to be cooled and a compartment beneath said chamber for containing mechanical refrigerating apparatus, said compartment having an inlet for air currents and an outlet for the same adjacent the top of the compartment, of a deflector disposed above said apparatus for directing said air currents towards said outlet and away from the bottom of said chamber, a second deflector above and in spaced relation to said first deflector, and means providing for movement of air between said deflectors.

11. In a refrigerator cabinet the combination with a chamber to be cooled and a compartment beneath said chamber for contain-

ing mechanical refrigerating apparatus, said compartment having an inlet for air currents and an outlet for the same adjacent the top of the compartment, of a deflector disposed above said apparatus for directing said air currents toward said outlet and away from the bottom of said chamber, a second deflector above said first deflector, and means providing for movement of air on both sides of said second deflector.

12. In a refrigerator cabinet the combination with a chamber to be cooled and a compartment beneath said chamber for containing mechanical refrigerating apparatus, said compartment having an inlet for air currents and an outlet for the same adjacent the top of the compartment, of a deflector disposed above said apparatus for directing said air currents toward said outlet and away from the bottom of said chamber, and a second deflector above said first deflector and in spaced relation both to the latter and to the bottom of said chamber, said cabinet providing inlet and outlet openings connecting with the space above and below said second deflector.

13. A refrigerator cabinet having a chamber to be cooled, a compartment beneath said chamber, and refrigerating apparatus, at least a part of which is disposed in said compartment, said compartment having inlet and outlet openings adjacent the bottom and top respectively, and a plurality of combined deflecting and reflecting members in said compartment and above said apparatus therein.

14. A refrigerator cabinet having a chamber with walls of insulating material, a compartment beneath said chamber, apparatus for extracting heat from said chamber, a part of said apparatus being disposed in said compartment, a plurality of sheet metal deflectors above said apparatus and beneath said chamber, and means providing for movement of air above and below said deflectors.

15. A refrigerating cabinet having a chamber with walls of insulating material, a compartment beneath said chamber, apparatus for extracting heat from said chamber, a part of said apparatus being disposed in said compartment, a plurality of sheet metal deflectors above said apparatus and beneath said chamber, said cabinet providing inlet and outlet openings permitting movement of air above and below each of said deflectors whereby heat developed in said compartment is prevented from reaching the bottom of said chamber.

Signed by me at Detroit, in the county of Wayne, and State of Michigan, this 2d day of March, 1927.
